(57) **CLAIM**

The ornamental design for a wheel, as shown and described.

DESCRIPTION

FIG. 1 is a perspective view of a wheel showing my new design;

FIG. 2 is a front elevational view of the wheel of FIG. 1;
FIG. 3 is a left side elevational view of the wheel of FIG. 1;
FIG. 4 is a right side elevational view of the wheel of FIG. 1;
FIG. 5 is a top plan view of the wheel of FIG. 1; and,
FIG. 6 is a bottom plan view of the wheel of FIG. 1; those
features not shown in the views of FIGS. 1-6 are disclaimed as
forming no part of the claimed design.

1 Claim, 5 Drawing Sheets
